(57) **CLAIM**

The ornamental design for a door sill portion, as shown and described.

DESCRIPTION

FIG. 1 is a perspective view of the top, side and front of a first embodiment of the new design.

FIG. 2 is a left side elevation view of a first embodiment of the new design. The right side elevation view of the first embodiment is a mirror image of the left side elevation view. FIG. 3 is a front elevation view of a first embodiment of the new design.

FIG. 4 is a top plan view of a first embodiment of the new design. No claim is made to ornamentation on the rear elevation view or bottom plan view so these views are not shown.

FIG. 5 is a perspective view of the top, side and front of a second embodiment of the new design. In the second embodiment, no tread pattern is shown on the top, front portion of the door sill.

FIG. 6 is a left side elevation view of a second embodiment of the new design. The right side view of the second embodiment is a mirror image of the left side view.

FIG. 7 is a front elevation view of a second embodiment of the new design; and,

FIG. 8 is a top plan view of a second embodiment of the new design. No claim is made to ornamentation on the rear elevation view or bottom plan view so these views are not shown.

Draining hole covers on the front of the sill portion are shown in broken lines in the views of the first and second embodiments of the new design.

The broken lines are for illustrative purposes only and form no part of the claimed design. The brackets indicate that the precise length of the door sill portion is not claimed.
